(57) **CLAIM**

The ornamental design for a dog boot, as shown and described.

DESCRIPTION

FIG. 1 is a perspective view of a dog boot showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the dog boot with an exemplary strap in a first position; and,

FIG. 10 is a perspective view of the dog boot with an exemplary strap in a second position.

The broken lines of FIG. 9 and FIG. 10 depicting a strap represent environmental structure that forms no part of the claimed design.
